UNITED STATES PATENT OFFICE.

CLARENCE E. SIEGFRIED, OF AKRON, OHIO, ASSIGNOR OF ONE-HALF TO WORTHINGTON HOYT, OF CLEVELAND HEIGHTS, OHIO.

NON-SKID CUSHION SUCTION-HEEL.

1,303,841.

Specification of Letters Patent. Patented May 13, 1919.

Application filed January 31, 1919. Serial No. 274,284.

To all whom it may concern:

Be it known that I, CLARENCE E. SIEGFRIED, a citizen of the United States, residing at Akron, in the county of Summit and State of Ohio, have invented new and useful Improvements in Non-Skid Cushion Suction-Heels, of which the following is a specification.

This invention relates to improvements in rubber or cushion lifts for application to heels of boots or shoes and the object of the invention is to provide a lift possessing superior means for attachment to the heel of a boot or shoe and also equipped on the road or pavement-engaging surface with means for preventing slipping and insure safety to the user of the same. It is also an object to provide a lift having good wearing qualities and which when attached to a heel will be held securely in position and prevent the entrance of water or foreign matter between the lift and the heel.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and modifications can be resorted to which come within the scope of the matter herein-after claimed.

In the drawings in which similar reference numerals indicate like parts in the different figures,

Figure 1 is a plan view of the under or road engaging face of a lift embodying the present invention.

Fig. 2 is a sectional view taken approximately on line 2 of Fig. 1 showing the lift in its inoperative or detached position, and

Fig. 3 is a sectional view taken on line 3 of Fig. 1 of a heel with the lift in Figs. 1 and 2 in operative position thereon.

The lift which constitutes the present invention comprises a body 1 of resilient material, preferably vulcanized rubber having the heel engaging surface 2 concave to form an arcuate or cup-shaped wall. The outer or lateral walls 3 of the lift are shaped to conform to the normal outlines of the heel in connection with which the lift is used while the same may be trimmed to accommo-

date it to the purpose for which it is intended. The road or pavement engaging face which is the lower one when the heel is in operation and the upper one in the drawings in general contour to the outer lateral walls 3 of the heel but considerably smaller and spaced therefrom. Surrounding the area or zone 4 are a series of zones 5, 6, 7 and 8 arranged in successive formation with each of them successively lower than the central member or zone 4 when the latter is in the position shown in Fig. 2, the arrangement for this face of the lift is substantially that of a terrace formation and the different portions 4 to 8 inclusive are connected by abrupt shoulders 9. Extending through the body member 1 and preferably located in spaced relation in the terrace or step 6 are a series of nail holes 10 preferably formed in lift 1 during vulcanization by the use of suitable pins for this purpose while the lift is in the mold and surrounding each of the openings 10, and positioned in, and wholly embedded in the material of the body 1 are washers 11 which are spaced from both the upper and lower faces of the lift. The lift is secured in position by applying the lift with its concave face 2 against the under face of the heel of a boot or shoe and then suitable nails 12 are driven through the openings 10 until the heads of the nails engage the washers 11 and as the nails are driven to place the entire body 1 of the lift is forced against the heel 13 so that the abutting faces of the lift and heel are substantially in the same plane and in constant contacting engagement. The forcing of the central portions of the lift against the heel 13 by means of the nails 12 causes a snug engagement between the lift and the heel and also distorts the stepped or road-engaging face of the lift so that when in operative position and ready for use the various steps 4 to 8 in connection with the shoulders 9 form triangularly-shaped grooves having outwardly-projecting working edges 15 for engagement with the ground or pavement and constitute means for preventing slipping and to a certain extent provide a cup-shaped engagement with the road for assisting in preventing any lateral movement of the shoe.

I claim,

An elastic lift for boots or shoes comprising a body of resilient material conforming

in general outlines to the heel, the heel engaging face of the lift being concave and adapted to be compressed in snug engagement with the heel for effecting a vacuum cup action, fastening means extending through the lift and engaging the heel, the road engaging face of the lift provided with a central horn which when the lift is unattached to the heel projects downwardly beyond the remaining portions of the lift, the balance of the road-engaging face of the

lift being fashioned with steps extending throughout the entire face, whereby when said lift is attached to the heel, said steps provide a series of teeth triangular in cross section extending over the entire surface of the lift with the exception of the central zone.

In testimony whereof I have hereunto set my hand.

CLARENCE E. SIEGFRIED.
